US0D1057157S

(12) **United States Design Patent** (10) **Patent No.:** **US D1,057,157 S**
(45) **Date of Patent:** ** *Jan. 7, 2025

(54) **SCANNER**

(71) Applicant: **KONINKLIJKE PHILIPS N.V.**
Eindhoven (NL)

(72) Inventor: **Ozgur Tasar**, Eindhoven (NL)

(73) Assignee: **KONINKLIJKE PHILIPS N.V.**
Eindhoven (NL)

(*) Notice: This patent is subject to a terminal disclaimer.

(**) Term: **15 Years**

(21) Appl. No.: **29/833,662**

(22) Filed: **Apr. 6, 2022**

(30) **Foreign Application Priority Data**

Oct. 6, 2021 (EM) 008715015-0001

(51) **LOC (15) Cl.** **24-01**

(52) **U.S. Cl.**

USPC **D24/159**

(58) **Field of Classification Search**

(57) **CLAIM**

The ornamental design for a scanner as shown.

DESCRIPTION

FIG. 1 is a perspective view showing a scanner design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings depict portions of the scanner and form no part of the claimed design.

1 Claim, 7 Drawing Sheets
